RAYMOND D. HYATT, OF COLUMBUS, OHIO, ASSIGNOR TO THE D. L. AULD COMPANY,
OF COLUMBUS, OHIO, A CORPORATION OF OHIO

LOCKING DEVICE

Application filed September 10, 1928. Serial No. 305,009.

The object of this invention is to provide a convenient and effective means for securing parts together, and especially for securing name plates to the radiator shells of automobiles.

It is also an object of this invention to provide a means by which the name plate can be first attached to an ornamental plate, and being so attached may be shipped or transported in assembled condition for application to the radiator shell of an automobile.

It is also an object of this invention to provide a device of this kind in which the parts are simple and may be readily assembled, and when so assembled may be taken apart for the replacement of old or unused parts.

For the purpose of illustration there is shown in the accompanying drawings a preferred embodiment of this invention.

20 Referring to the drawings:

Figure 1 is a face view of a name plate of a form such as that now generally used on a certain type of cars.

Figure 2 is a side view of the same plate, 25 showing the attaching means affixed thereto.

Figure 3 is a face view of an ornamental plate, to which the name plate is attached.

Figure 4 is a side view of the cup means by which the name plate is attached to the 30 ornamental plate.

Figure 5 is a view showing the name plate, the ornamental plate assembled and in dotted line the location of the locking member.

Figure 6 is a section on the line 6—6 of 35 Figure 3.

Figure 7 is a section on the line 7—7 of Figure 5, but showing the plates assembled on a radiator shell.

There is shown in Figure 1 a name plate, 40 such as is used in connection with this invention. To this name plate the locking means is attached by means of solder or some other convenient means.

The locking means is located to one side 45 of the longitudinal axis of the name plate. The locking member as a whole is designated by the numeral 2, which is cup shape with a rather flaring open mouth. The bottom of the cup member is the part that is directly 50 united to the name plate. The outer edge

of the cup extends outwardly in the form of a flange 3, which is directed somewhat downwardly and provides a resilient flange means for attaching the plate to the radiator shell of an automobile. This cup device is shown in Figure 4, somewhat enlarged. The point at which the cup is united by solder to the name plate is indicated by the numeral 4.

The diametrically opposite sides of the walls of the cup are slit to form lugs 5. 60 These slits are fully shown in Figure 4, by the reference character 5'. It is by means of these lugs that the name plate is united to the oval or ornamental plate, shown in Figure 3. The ornamental plate 6 has 65 formed therein a depression, or seat 7, of the same shape and size as that of the name plate and of substantially the same depth. The name plate is received in this depression and held therein by means of the locking device. 70

In the center of this depression, in the oval plate, there is formed an opening, one side of which is substantially semicircular in shape, indicated by the numeral 8, of substantially the same diameter as that of the flange of the locking device, while the other part of the opening, indicated by the numeral 9, is smaller and substantially semi-circular in shape, having a diameter substantially equal to that of the bottom of the cup. 75

The opening 8 is sufficiently large to accommodate the flange 3 of the cup so that it may be made to extend through the opening, and after being placed therein the locking means is moved so as to bring the lower part 80 of the cup part into engagement with the circular part of the opening, indicated by the numeral 9. When in this position the lugs 5 engage the side of the opening and hold the name plate in firm engagement with the oval or ornamental plate. 90

When the name plate is first assembled with the locking device it is similar to that shown in Figure 2. In Figure 3 there is shown the oval plate in a condition for the application of the name plate and the locking means to it. In order to apply the name plate to the oval plate the flange part of the cup is extended through the larger part of the opening in the oval plate, in such a way that 95 100

it will entirely pass through and engage the opposite side of the oval plate. When in this position the name plate is adjusted so that the plate will suitably fit within the depression 7 and the lugs are forced into the narrow part of the opening and thereafter the name plate is seated within the depression 7.

While the parts are in this condition the name plate and the oval plate may be conveniently transported from one place to another, or even the parts in this assembled condition may be forwarded in the mail. The parts are sufficiently secured together that under ordinary conditions they will not be forced apart.

When the parts are assembled as here described and illustrated in Figure 5, the ornamental or oval plate, together with the name plate, are forced into engagement with the radiator shell. The radiator shell is indicated by the numeral 10, and has formed therein a recess or depression 11 of the same shape and size as that of the oval or ornamental plate.

In the center of the oval depression there is formed an opening, which is a punched and a drawn-out hole, indicated by the numeral 12. Around this hole is a flange 13. The opening in this radiator shell 10 is just sufficient to receive the flange part 3 of the locking device and to hold it in secure and tight relation thereto; in fact, the parts are pressed together and on account of the resiliency of the flange the flange somewhat yields and bends, and rigidly and frictionally engages the flanges 13 of the opening 12.

Since any pressure to force the locking means into the opening 12 tends to cup the flange 3, any reverse action would tend to straighten out this cup and to cause the edges of the flange 3 to bite into the side of the flange 13 and securely hold the parts in assembled relation, making it almost impossible to accidentally remove the parts after they have become assembled in the radiator shell. However, before they are assembled in the shell the parts can be easily removed and replaced.

If, however, the name plate should become marred or the oval ornamental plate become marred or ruined, they can both be removed from the radiator shell and replaced in the same manner that the original was placed in position.

It will be observed from an examination of Figure 7 that in the first instance the locking means holds the ornamental plate in assembled relation with the name plate, and that in the final assembling of the plates on a radiator shell the locking means holds the name plate to the radiator shell and that it holds the ornamental or oval plate.

Having thus fully described my invention, what I claim is new and desire to secure by Letters Patent, is:

1. In a locking device, a name plate, a cup-like member attached to said name plate and having outwardly extending flanges thereon and a pair of lugs, an ornamental plate having a depression therein to receive the name plate and a curved wall opening therein having a part on one radius and another part on another radius, said flange of said cup-shaped means adapted to pass through one part of said opening and the lugs to engage another part of said opening to lock the parts in relation to each other when the name plate is seated within the depression on the ornamental plate.

2. In combination with a radiator shell, a name plate and an ornamental plate, locking means attached to the name plate and adapted to engage the ornamental plate and the radiator shell to hold them in assembled relation to each other.

3. In combination with a radiator shell, a name plate having a plurality of locking means thereon, an ornamental plate having a depression therein to receive the name plate, and an opening therein, said opening removably receiving the locking means and the wall of said opening being engaged by one of said means to hold the name plate with the ornamental plate, the other of said locking means adapted to engage the radiator shell to hold the two plates and the radiator shell assembled.

4. In combination with a supporting member, a name plate, a second plate, a cup-shaped locking member on said name plate having a means to engage and hold said second plate to the name plate, and a second means to engage the supporting member to hold and support both of said plates.

5. In combination with a supporting member having a hole therein, a name plate, a second plate, a cup-shaped locking member on said name plate having studs thereon to engage and hold said second plate to the name plate, and a second means to engage in the hole of said supporting member to hold and support both of said plates.

6. In combination with a supporting member having a flanged hole therein, a plate having a hole therein, a second plate, and a cup-shaped locking means on said second plate having lugs to engage and hold said first plate and a resilient flange to engage the flange of said supporting member to hold and support both of said plates.

7. In combination with a supporting member, a plate having a hole therein, a second plate, and a cup-shaped locking member on said second plate adapted to engage the sides of said hole and said supporting member to hold the plates together and support them.

8. In combination with a radiator shell having a circular flange thereon, a plate having a hole therein, a second plate, and a locking means on said second plate adapted to

extend through the hole in the first plate, said locking means having lugs to engage the sides of said hole and a resilient flange to engage said circular flange whereby the plates are held together and supported by said shell.

5 9. In combination with a supporting member, an ornamental plate having a hole therein with two semi-circular parts on different radii, a name plate, and means on said name plate to pass through said hole and lock the plates to said supporting member, said means including a part just passing through the larger part of the hole to engage the supporting member, and a smaller part to engage the smaller part of said hole to lock the plates together.

10 10. In combination with a radiator shell having a hole therein, an ornamental plate having a hole therein with parts of different size, a name plate, and locking means on said name plate, said locking means including a part just passing through the larger part of said ornamental plate hole to engage the hole in the shell to lock the plates to the shell, and a smaller part to engage the smaller part of said hole to lock the name plate to the ornamental plate.

15 In testimony whereof, I affix my signature.
RAYMOND D. HYATT.
